CHRISTIAN F. LAUN, OF WATERVILLE, CONNECTICUT, ASSIGNOR TO BERBECKER & ROWLAND MANUFACTURING COMPANY, OF WATERVILLE, CONNECTICUT, A CORPORATION OF CONNECTICUT.

FURNITURE-CASTER.

1,029,136.

Specification of Letters Patent. Patented June 11, 1912.

Application filed November 4, 1911. Serial No. 658,518.

To all whom it may concern:

Be it known that I, CHRISTIAN F. LAUN, a citizen of the United States, and a resident of Waterville, in the county of New Haven 5 and State of Connecticut, have made and invented certain new and useful Improvements in Furniture-Casters, of which the following is a specification.

My invention relates to an improvement 10 in furniture casters, and more particularly to that type or style thereof commonly known to the trade and public as "furniture glides," and comprising a shell of metal in the form of a hollow sector of a sphere 15 and provided with means whereby to attach it to the leg of a chair or other article of furniture. Heretofore these glides have been generally made from one piece of metal the upturned peripheral flange being provided with teeth or spurs to be forced into 20 the wood of the article with which they are used and so secure it in place. Certain objections, however, have been urged against this structure, particularly that of the liability of splitting the wood to which the article is attached, in that the teeth or spurs must necessarily be of sufficient size in order 25 to penetrate the wood to a considerable distance in order to prevent the glide from becoming disengaged from the article of furniture. Furthermore, the article being made of glass-hardened metal, the peripheral teeth or spurs are necessarily very brittle, and oftentimes break or crack off in the operation of driving them into the furniture, 30 particularly when constructed of hard wood. In order to overcome these objections, it has been attempted to construct the glide with a central nail projecting from the concave side thereof, the teeth or spurs on the rim of 35 the glide being formed of such size only as to slightly penetrate the wood in order to prevent it from turning, the central nail being relied upon for securing the glide in place. This form of glide, however, has only 40 been partially successful, owing to the fact that it must be hardened or tempered to impart to it the necessary wear resisting qualities. If the central nail be secured to the 45 glide prior to the hardening of the metal, it becomes loose, owing to the difference in the expansion and contraction of the different metals used for the nail and dome. If the 50 shell be hardened or tempered prior to se-

curing the nail thereto, it is found to be 55 difficult, if not impossible, to upset the metal of the shell around the nail in order to hold the latter in position.

It is the purpose of my invention to overcome these objections and to produce a glide 60 wherein the central nail may be utilized for securing the article in place and at the same time employ a cup or shell of hardened or tempered metal, the completed glide comprising novel details of construction herein- 65 after described and pointed out in the claim.

In the accompanying drawings, Figure 1 is a sectional view of the shell during one stage of its formation, and prior to being 70 hardened or tempered; Fig. 2 is a similar view of the completely shaped cup or shell and taken on the line 2-2 of Fig. 3; Fig. 3 is a bottom plan view thereof; Fig. 4 is a plan view of the blank of the spanner- 75 washer; Fig. 5 is a similar view of the same after being properly bent or shaped, and prior to having the attaching nail secured thereto; Fig. 6 is a sectional view of the spanner-washer taken on the line 6-6 of 80 Fig. 5, and showing the attaching nail secured thereto. Fig. 7 is a sectional view of the glide, the parts being shown partially assembled; Fig. 8 is a similar view thereof showing the parts fully assembled; Fig. 9 is 85 a bottom plan view of a modified form of the spanner-washer shown in Fig. 5; Fig. 10 is a sectional view of another form of spanner-washer having the central attaching nail secured thereto. Fig. 11 shows the 90 spanner-washer of Fig. 10 partially assembled with the shell, and Fig. 12 is a similar view showing these parts fully assembled.

By reference to these drawings it will be seen that my improved glide comprises three 95 parts, viz., an outer shell, a contained spanner-washer, and a securing nail attached to the latter, the outer shell being first formed as shown in Fig. 1, that is, of a cup-shaped disk 13 having a straight peripheral flange 100 14. This shell is then, by means of suitable dies or other tools, converted into the shape as illustrated in Fig. 2, that is, with in-turned locking flange 15, whereby, as hereinafter described, to securely lock the spanner-washer in place. This outer shell or cup is made of such steel or other metal as can be glass-hardened in order to impart 105

thereto the desirable wear resisting qualities, this step in the manufacture of the article occurring after the outer shell has been properly and completely shaped as 5 illustrated in Figs. 2 and 3.

The spanner-washer, preferably formed from soft or mild steel, is first blanked out as illustrated in Fig. 4, that is, with the V-shaped parts 16, subsequently converted into 10 spurs or teeth, the metal between the parts 16 and arms 17 being cut away, and with a central opening 18, this hole or opening for the reception of the headed end of the attaching nail being formed by forcing a 15 proper tool through the metal as distinguished from cutting the metal out to form the same, the bur formed around the opening being utilized for assisting in holding the nail 19 in place. After the formation of 20 the blank as illustrated in Fig. 4, it is then shaped as illustrated in Figs. 5 and 6, that is, the V-shaped parts 16 are bent downwardly to form the teeth or spurs 20, the arms 17 being provided with an elevated 25 ridge or flute 21 somewhat decreasing the diameter of the washer. The nail 19 is assembled with this washer and securely locked thereto, the bur around the central opening in the washer assisting in securing the nail 30 tightly in position as before described, the completed spanner-washer being illustrated in Figs. 6 and 7. In assembling the parts thus formed, the spanner-washer is placed within the outer cup or shell, and securely 35 locked thereto by flattening out the ridge or flute 21, the diameter of the washer being thereby increased and causing the extreme outer edge of the same to be locked and held within the inturned flange 15 of the outer 40 shell, and practically forming a solid glide, as illustrated in Fig. 8.

It will of course be understood that several changes or variations might be made in the form of the spanner-washer, as, for instance, as shown in Fig. 9, but three teeth or spurs 22 may be formed, instead of four, as illustrated in Fig. 4. While the number of teeth may be increased or decreased as desired, I have in practice found that three 45 are preferable. Furthermore, instead of cutting away the metal adjacent the teeth as illustrated in Figs. 4 and 5, the V-shaped portions 23 may be cut out of the washer between the teeth. Again, instead of forming a ridge or flute in the spanner-washer as 50

above described, it may be constructed as illustrated in Figs. 10, 11 and 12, that is, of a disk-like portion 24 with an inturned flange 25, which latter, when operated upon by proper tools, will spread from the shape 60 as illustrated in Fig. 11 to that in Fig. 12, thereby securely locking the washer in position within the inturned edge of the outer shell.

From the foregoing it will be understood 65 that the cup or outer shell may be made of any desired thickness, two or three times the thickness of the ordinary glide if so desired, imparting thereto a correspondingly longer life. The teeth or prongs may be made of 70 any length desired, and, coming as they do closer to the center of the glide, are much less apt to split the wood of the furniture than when formed on the outer edge of the glide. Furthermore, these teeth can be made 75 of comparatively small size as they perform no function other than to prevent the glide from turning or twisting after being secured to the furniture, the central nail permitting the glide to be much more easily secured in 80 place than in those instances where the prongs are used as the attaching means. It might also be added that the spanner-washer in the finished article materially reinforces the outer shell and assists in preventing the 85 latter from being cracked or broken by the hammer or other tool used in securing the glide in place, particularly in the cheaper forms of articles wherein the cup or outer shell is made of comparatively thin stock. 90

What I claim is:

In a furniture caster, the combination 95 with an outer shell of curved form in cross-section and having an inwardly turned locking edge, of a corrugated spanner washer located within said shell and having means for securing the caster to an article of furniture; said spanner washer being of a diameter such that it may pass within the inwardly turned edge aforesaid and enter said 100 shell, and the periphery thereof being forced beneath said locking edge by flattening the corrugations of said washer.

Signed at Waterville, in the county of New Haven and State of Connecticut, this 105 2nd day of November, A. D. 1911.

CHRISTIAN F. LAUN.
